CARD STOP MOTION

James H. Yon, Jr., Charlotte, N.C., assignor to Jeff Mfg. Corp., Charlotte, N.C., a corporation of North Carolina Filed Dec. 9, 1963, Ser. No. 329,004

8 Claims. (Cl. 19—25)

This invention relates generally to a stop motion for carding machines and more particularly to an improved stop motion which includes detector means that is normally held in one position by engagement with the sliver being formed by the carding machine and a control means which utilizes a pressurized fluid system to immediately stop the delivery end of the card when the detector means moves to a second position upon the sliver breaking or the tension in the sliver falling below a predetermined amount.

There have been many different types of card stop motions heretofore proposed which have operated to stop the card in response to a break or a reduction of tension in the sliver. These prior types of stop motions have included completely mechanical types as well as electrical types which require one or more electrical switches. However, these prior stop motions have not met with widespread commercial acceptance.

It is a primary object of the present invention to provide an improved card stop motion having components utilizing fluid pressure which may be easily installed on various types of carding machines without requiring any extensive modifications of the card and which is inexpensive to produce, and has a long useful life.

It is a more specific object of the present invention to provide an improved stop motion for a card which includes a detector element positioned in engagement with and normally held in a first position by the moving sliver as it is produced by the card, the detector being movable to a second position in response to a break or slackening of tension in the sliver and being operatively connected to a pressurized fluid system which is operable to control the operation of the sliver delivery end of the card, the pressurized fluid system including a fluid control valve which is connected to a source of fluid under pressure and is operated in response to the detector, and a fluid controlled cylinder that is operatively connected to the fluid control valve and has a movable piston that is connected to and controls the operation of the sliver delivery end of the card.

It is another object of the present invention to provide a manually operable fluid valve, as a component of an improved card stop motion of the type described, wherein the valve can be moved to a position to override the normal stopping function of the stop motion when the sliver is slack, as for example when initially starting up the card or when piecing up a broken end.

Some of the objects of the invention having been stated, other objects will appear as the description proceeds, when taken in connection with the accompanying drawings, in which:

FIGURE 1 is a side elevation of the delivery end portion of a carding machine with the improved stop motion of the present invention associated therewith;

FIGURE 2 is an enlarged fragmentary front elevation taken in the direction of the arrow 2 of FIGURE 1 showing the manner in which the detector or sensing element of the present card stop motion is engaged by the sliver being produced by the card;

FIGURE 3 is a fragmentary sectional plan view taken substantially along the line 3—3 in FIGURE 2;

FIGURE 4 is an enlarged fragmentary sectional plan view taken substantially along the line 4—4 in FIGURE 1 and illustrating the control piston which operates to

2

shift the drive belt and control the operation of the delivery end of the carding machine;

FIGURE 5 is a fragmentary vertical sectional view taken substantially along the line 5—5 in FIGURE 4;

FIGURE 6 is an enlarged vertical sectional view taken substantially along the line 6—6 in FIGURE 3; and

FIGURE 7 is a somewhat schematic diagram illustrating the manner in which the fluid control valves operate in response to movement of the sliver detector and showing the connection of the fluid lines between these valves and the fluid controlled operator piston.

The conventional parts of the carding machine which are shown in the drawings will first be described and then the improved stop motion of the present invention will be described in association therewith. Only the front or delivery end of a conventional carding machine is shown in the drawings because this is the only part of the card that is controlled by the present invention.

As shown in FIGURE 1, the card includes a main cylinder or swift 10 which is supported for rotation in a conventional manner on the main frame 11 of the card. The fibers are conventionally transferred from the main cylinder 10 to a doffer cylinder 12 which is also supported for rotation on the frame 11. The fibers are then removed from the doffer cylinder 12 in a conventional manner, usually by a reciprocating comb or doffer blade, not shown, to form a forwardly moving web of fibers which converge and pass through a trumpet, not shown. The thin web of fibers is condensed by the trumpet to form a strand that is immediately passed between a pair of driven calender rolls 15 and 16 and emerges as a sliver S.

The sliver S moves upwardly from the calender rolls 15 and 16 (FIGURE 2) and is drawn through a second trumpet, not shown, as it is drawn into a coiler head mechanism 20. The coiler head 20 is supported on the upper end of a drive shaft housing or column 21, the lower end of which is fixed in a coiler can platform 22 (FIGURE 1). A sliver receiving coiler can 23 is supported at its lower end on the platform 22 and is rotated thereby as the sliver S is drawn through the coiler head 20 and fed into the can 23 in a conventional manner.

A driving belt 35 (FIGURES 1 and 4) extends forwardly from the input end of the card, not shown, and engages a barrow pulley 36 which is fixed on one end of a delivery end power shaft 37. The delivery end power shaft 37 has a relatively small barrow pinion 38 fixed thereto adjacent the barrow pulley 36 (FIGURE 4). This end of the delivery end power shaft 37 is supported for rotation in the medial portion of a knock-off lever 40, one end of which is pivotally supported on the frame 11 (FIGURE 1) and the other end of which is normally supported by a cam lever 41 which is pivoted on the frame 11.

When the knock-off lever 40 is supported in the position shown in FIGURE 1 by the cam lever 41, the small barrow pinion 38 drivingly engages the teeth of a large doffer cylinder drive gear 42 which is fixed on one end of the supporting shaft of the doffer cylinder 12. The doffer gear 42 in turn drivingly engages a train of drive gears, not shown, which are supported for rotation in a gear housing 43 (FIGURE 1). The gears in the housing 43 impart rotation to a calender roll drive shaft 44 (FIGURE 2) which extends inwardly from the gear housing 43. The lower calender roll 16 is fixed on the drive shaft 44 and the upper calender roll 15 is driven by means of conventional drive gears, not shown, which are supported in a gear housing 45. The drive gears in the housing 45 are drivingly connected to a vertically disposed drive shaft, not shown, which is supported in the drive column 21 to impart rotation to the coiler head mecha-

nism 20 as well as the coiler can drive mechanism in the coiler can platform 22.

Thus, when the knock-off lever 40 is supported by the cam lever 41, as shown in FIGURE 1, and the belt 35 is in engagement with the barrow pulley 36, as shown in FIGURE 4, motion is imparted to the delivery end of the card in timed relationship to rotation of the main cylinder 10 by means of the barrow pinion 38 on the power shaft 37, the doffer cylinder gear 42, and the trains of gears within the gear housings 43 and 45. The sliver S produced by the card is thus maintained at a predetermined tension as it is fed from the calender rolls 15, 16 and into the coiler head mechanism 20.

In many carding machines, it is left to the operator to stop the delivery end of the card when the sliver S is broken or becomes unusually slack or untensioned. In many instances, the operator will not observe the malfunction until the sliver has run out onto the floor and has accumulated a great amount of waste. Then, the operator can stop the delivery of the sliver S by manually moving the cam lever 41 to allow the outer end of the knock-off lever 40 to move downwardly and lower the barrow pinion 38 out of engagement with the doffer gear 42. After the defect in the sliver S has been corrected, the operator can start the delivery of the sliver S by raising the outer end of the knock-off lever 40 to raise the power shaft 37 and move the pinion 38 back into driving engagement with the doffer gear 42. The cam lever 41 is then moved to the position shown in FIGURE 1 to support the outer end of the knock-off lever 40 in driving position.

This manual raising and lowering of the knock-off lever 40 to start and stop operation of the delivery end of the card has been objectionable because of the sudden starting and stopping and many times the gear teeth on the pinion 38 and gear 42 are broken. In order to overcome these objections, many carding machines are provided with an idler pulley 48 (FIGURE 4) which is supported for free rotation on the shaft 37 and positioned adjacent the barrow pulley 36. In order to stop operation of the delivery end of the card, the driving belt 35 may be shifted from the barrow pulley 36 to the idler pulley 48, as shown in dotted lines in FIGURE 4, and the pinion 38 can remain in engagement with the doffer gear 42. In the card heretofore described, the sliver delivery end can be stopped and started by movement of the knock-off cam lever 41 and knock-off lever 40 or by movement of the belt 35 between the pulleys 36 and 48. Since either of these means can be operated to control the operation of the sliver delivery means, they will be referred to generally as means for controlling the advance of the sliver and the improved stop motion, which will now be described, can be adapted to operate either of these means.

In the present instance, the improved stop motion includes means to shift the delivery end drive belt 35, however, it could be easily adapted to operate the cam lever 41 to control the position of the knock-off lever 40. The stop motion includes means for detecting a break or slackening of tension in the sliver S or what is generally referred to as a sliver detector, which includes a trough-shaped guide or spoon 50 which is suitably secured to the upper end of a control rod 51. One end of a counterweight support rod 52 (FIGURE 2) is supported for vertical adjustment adjacent the upper end of the control rod 51 and, in the present instance, the inner end of the support rod 52 is supported in a vertically adjustable collar which surrounds the control rod 51. The outer end of the support rod 52 has a counterweight 53 supported for longitudinal adjustment thereon.

The lower end of the control rod 51 is pivotally supported as at 55 (FIGURE 6) at one end of a support bracket 56. The free end of the support bracket forms the lower end back walls of a control box which is provided with a removable cover 57 that is suitably secured in position thereon. The other end of the support bracket 56 is suitably supported for vertical and radial adjustment on the drive shaft support housing 21.

A guide tube 53 is suitably secured to the front upper portion of the cover 57 (FIGURES 3 and 6) for engagement by the sliver S as it is guided upwardly to the detector spoon 50. As the lower portion of the control lever 51 passes through an opening in the cover 57 of the control box, it passes through a resilient bellows type boot 60 which is suitably connected to the box cover at its lower end and at its upper end to the control lever 51 (FIGURE 6). The lower portion of the control rod 51 engages the outer free end of a control plunger or movable element 61 which extends into valve means which include a fluid valve housing 62 that is supported within the control box at the end of the support bracket 56 (FIGURE 6). The valve housing 62 contains a pair of fluid control valves, which are shown schematically at 62a and 62b in FIGURE 7. The valves 62a and 62b are normally held in the solid line position shown by the control plunger 61 (shown in dotted lines in FIGURE 7) which is maintained in engagement with the control rod 51 by yieldable urging means such as spring 77 and the control rod 51 when the moving sliver S is properly tensioned. Secondary valve means which includes a manually operable fluid control valve 63 (FIGURES 3 and 7) is also supported within the control box. The fluid control valves 62a, 62b and 63 and the manner in which they operate will be presently described.

As best shown in FIGURES 4 and 5, a bracket 65 is removably secured to a vertically extending rib of the card frame 11 and has one end of pneumatically operated actuating means such as a fluid operated cylinder 66 suitably secured thereto. A piston 67 is mounted for longitudinal movement inside of the cylinder 66 and has a piston rod which is suitably connected to a belt shifter 70. The belt shifter 70 is shown as a flanged rotatable member supported for free rotation on the piston rod and with the flanges adapted to engage and guide the drive belt 35 to shift the same between the pulleys 36 and 48. When the piston 67 is moved to the opposite end of the cylinder 66, from the position shown in FIGURE 4, the shifter 70 and the belt 35 will be shifted to the dotted line position and from the barrow pulley 36 to the idler pulley 48 to stop the operation of the delivery end of the card. Then, when the piston 67 is withdrawn back into the cylinder 66 to the position shown in FIGURE 4, the belt 35 will be shifted from the idler pulley 48 and onto the barrow pulley 36 to again start operation of the delivery end of the card. The cylinder 66, piston 67 and belt shifter 70 make up the pneumatically operated actuating means which is operatively connected to the control means that controls operation of the delivery end of the card.

While the valves 62a, 62b and 63, as well as the cylinder 66, could be of the hydraulic type and connected to a suitable source of hydraulic fluid under pressure, it is preferred that they be of the type that operate on compressed air, since most textile mills already have suitable sources of compressed air which are used for cleaning and blowing lint off of the machines. As shown in FIGURE 7 first conduit means are provided by means of which, the valve 62a is connected by a line 72 to one end of the cylinder 66 and the valve 62b is connected to the opposite end of the cylinder 66 by a line 73. Second conduit means are also provided for connecting the valves 62a, 62b to an associated source of fluid pressure which include line 74 is connected at one end to the manually operable valve 63 and its other end is branched to form branch lines 74a and 74b that are connected to the valves 62a and 62b. A main air supply line 75 is connected at one end to the manual valve 63 and its opposite end is suitably connected to any convenient source of compressed air, schematically indicated at 76.

As is schematically indicated in FIGURE 7, each of the valves 62a, 62b and 63 have ball-type valve elements having one flat or recessed surface and upwardly extending operating levers connected to the valve balls. Each of the valves is provided with an annular air passageway

which surrounds the ball valve and is adapted to be communicated with the inlet and exhaust ports.

The plunger 61 controls movement of the operating levers of the valves 62a, 62b between the solid and dotted line positions shown in FIGURE 7 and the plunger 61 normally maintains the levels in the solid line position shown by pressure of the control rod 51 against the plunger 61 yielding urged by the spring 77 into engagement with the control rod 51. When a break in the sliver S occurs to release the pressure on the control rod 51, the spring 77 moves the plunger 61 and the levers and ball valves of the valves 62a and 62b to the dotted line positions shown, so that the air supply line 74a is connected to the line 72 and the piston 67 will move to the opposite end of the air cylinder 66 and move the belt 35 onto the idler pulley 48. Since the ball valve in the valve 62b is moved to the dotted line position, the line 73 is connected to the exhaust port of the valve 62b so that the air on the opposite side of the piston 67 is exhausted as the piston moves from right to left in FIGURE 7.

When the card is operating properly and the sliver S, extending between the calender rolls 15, 16 and the coiler head 20, is under the proper tension, the control arm 51 will be held in the position shown in FIGURES 2 and 7 so that the plunger 61 will be pushed inwardly to maintain the valves 62a and 62b in the positions shown in FIGURE 7. Then, compressed air can enter through the line 74b and pass through valve 62b and line 73 and maintain the piston 67 of the air cylinder 66 in an innermost position so that the drive belt 35 will remain in engagement with the barrow pulley 36 to continue operation of the delivery end of the card.

The manually controlled overriding valve 63 may be switched to the dotted line position shown to prevent the compressed air from entering the line 74 and then movement of the valves 62a and 62b will not cause movement of the belt shifter 70. Thus, the valve 63 can be moved to the dotted line position and the delivery end of the card can be operated even if the sliver S does not have sufficient tension against the spoon 50 to hold the control rod 51 against the plunger 61 with enough force to maintain the valves 62a and 62b in the solid line position shown in FIGURE 7. For example, after a break occurs in the sliver S, it is necessary to operate the delivery end of the card for some time before the proper amount of tension is obtained in the moving sliver S.

After the proper tension has been obtained in the sliver S, the manual switch 63 may be moved to the solid line position and then operation of the card will be under control of the detector spoon 50. The amount of force that the detector spoon 50 applies against the moving sliver S can be adjusted by varying the vertical position of the support rod 52 on the control rod 51 and the longitudinal position of the counterweight 53 on the support rod 52.

In the drawings and specification there has been set forth a preferred embodiment of the invention and, although specific terms are employed, they are used in a generic and descriptive sense only, and not for purposes of limitation, the scope of the invention being defined in the claims.

I claim:

1. A stop motion for a carding machine comprising in combination, a movable sliver detector arranged to engage an advancing sliver formed by said carding machine, means on said carding machine for controlling the advance of said sliver, pneumatically operated means for actuating said control means, valve means including a movable element for operatively communicating said pneumatically operated actuating means with an associated source of fluid pressure, means for yieldingly urging said movable element against said sliver detector, said sliver detector with said movable element in engagement therewith being maintained in one position by said advancing sliver against said urging means to operate said pneumatically operated means with said fluid pressure through said valve means and actuate said control means for continuous advance

of said sliver, said sliver detector with said movable element in engagement therewith being movable to a second position by said urging means upon the occurrence of a break or a reduction in tension in said sliver to operate said pneumatically operated actuating means with said fluid pressure through said valve means and actuate said control means to stop the advance of said sliver.

5 2. A card stop motion in accordance with claim 1 including secondary valve means for disconnecting said associated source of fluid pressure from said valve means to prevent the operation of said pneumatically operated actuating means in the second position of said sliver detector and said movable element.

10 3. A card stop motion in accordance with claim 1 wherein said sliver detector includes a pivotally mounted rod having an upper end and wherein said movable element is yieldingly maintained in engagement with said control rod by said urging means, a trough-shaped guide on said rod upper end for guidably receiving said advancing sliver to maintain said rod and said movable element in said one position.

15 4. A card stop motion in accordance with claim 3 including a support rod supported at one end for longitudinal adjustment on said control rod and extending laterally therefrom at a right angle and a counterweight member supported for longitudinal adjustment on said support rod.

20 5. A card stop motion in accordance with claim 1 wherein said pneumatically operated actuating means includes a fluid pressure cylinder, a piston having a piston rod reciprocably movable within said cylinder and means connecting said piston rod to said means for controlling the advance of said sliver, said valve means being arranged to communicate said source of fluid pressure with said cylinder on one side of said piston to actuate said control means for continuous advance of the sliver when said sliver detector and movable element are in said one position and to communicate said source of fluid pressure to said cylinder on the other side of said piston when said sliver detector and movable element are in said second position to actuate said control means and stop the advance of said sliver upon the occurrence of a break or reduction in tension in said sliver.

25 6. A card stop motion in accordance with claim 5 wherein said means for controlling the advance of said sliver include means for advancing said sliver, a driving belt, a drive pulley arranged to be driven by said driving belt, means for connecting said drive pulley to said sliver advancing means, an idler pulley positioned adjacent said drive pulley and means connecting said piston rod to said driving belt to shift said driving belt from said drive pulley to said idler pulley when said source of fluid pressure is communicated with said cylinder on said other side of said piston to stop the advance of said sliver by said sliver advancing means.

30 7. A card stop motion in accordance with claim 1 wherein said pneumatically operated actuating means includes a fluid pressure cylinder, a piston having a piston rod reciprocably movable within said cylinder and means connecting said piston rod to said means for controlling the advance of said sliver, and wherein said valve means includes a pair of valves each having a movable valve element, first conduit means connecting said pair of valves to said cylinder on opposite sides of said piston, second conduit means connecting said pair of valves to an associated source of fluid pressure and wherein said movable element comprises a control plunger operatively connected to said pair of valves and wherein said urging means includes a spring for yieldingly urging said control plunger together with said sliver detector into said second position, said valve elements being movable by said plunger against said spring to communicate said source of fluid pressure through said second conduit means with said cylinder on said one side of said piston and simultaneously exhaust said cylinder from said other side of said piston through said first conduit means when said sliver detector and plunger are in said one position for continuous advance

of said sliver, said pair of valve elements being movable by said spring to communicate said source of fluid pressure with said cylinder on said other side of said piston and simultaneously exhaust said cylinder from said one side of said piston to actuate said control means through said piston rod when said sliver detector and plunger are in said second position to stop the advance of said sliver upon the occurrence of a break or a reduction in tension in said sliver.

8. A card stop motion in accordance with claim 7 including a manually operated valve in said second conduit means for communicating said associated source of fluid pressure with said pair of valves, said manually operated valve being operable to prevent the actuation of said control means through said cylinder when said sliver detector and plunger are in said second position for continuous advance of said sliver.
